TAPE DISPENSING APPARATUS AND
MOISTENING MEANS THEREFORTrevor R. Gautier, Nashua, N. H., assignor to
Nashua Gummed and Coated Paper Company,
Nashua, N. H., a corporation of Massachusetts

Application July 20, 1943, Serial No. 495,456

4 Claims. (Cl. 91—38)

My present invention relates to machines and apparatus for adhesively conditioning and delivering lengths of flexible strip material for package sealing, labeling and other purposes. More particularly it aims to provide in strip servers, tape dispensers and like devices of the class referred to improved initial or accessory equipment for insuring the desired application or coating of the moistening fluid under different operating conditions, subject to selective but predetermined control by the operator. In certain respects the present invention presents a further and improved embodiment of the generic subject matter of my copending application Serial No. 419,111, filed November 14, 1941.

In the drawings illustrating one embodiment of the present invention by way of example:

Fig. 1 is a side elevation of a gummed tape dispenser or strip server incorporating the improved means of the invention.

Fig. 2 is a plan of the Fig. 1 machine.

Fig. 3 is a corresponding front elevation with parts in vertical section.

Fig. 4 is a longitudinal vertical section of a forward portion of the machine.

Fig. 5 is an isometric view of a demountable moistening and liquid-level-controlling unit, such as that of Fig. 1, and

Fig. 6 is a side elevation partly in section of a portion of the assembly of Fig. 5.

Referring to the drawings in more detail, the machine as a whole here selected for the purposes of illustration may be understood as similar in general to those for example of my Patents Nos. 2,082,733 of June 1, 1937, Des. 111,568 of October 4, 1938, 2,138,474 of November 29, 1938, 2,192,132 of February 27, 1940, 2,290,041 of July 14, 1942, and others of this general class. It comprises a housing having spaced side frames 1 with appropriate cross connection, as at 8 in Fig. 3, outer ends of other cross members being apparent in Fig. 1. At its rear portion the housing is adapted to support a strip or tape supply in roll form, as in the well or basket 9 having a movable top cover 10, Fig. 2.

The tape or strip material from the supply roll is advanced past severing and moistening mechanism and delivered at the front of the machine. In its forward travel it is directed as by lower and upper guides 11, 12 (Fig. 4) to and between lower and upper feed wheels or rolls 13, 14, one of which, herein the lower roll 13, is driven.

Forwardly beyond the feed means the tape is moved past severing or cut-off mechanism, Figs. 1, 3 and 4, including fixed and movable blades

15 and 16, the latter pivotally supported as at 17 on a stationary part such as a lateral extension of the fixed blade.

The feeding and the severing means are actuated from an operating lever 20, Figs. 1 to 3, through connections and drive gearing which may be assumed as generally similar as in one or another of the patents mentioned. Such operating mechanism is disposed in part in a lateral compartment 22 on the right side frame and having a detachable side cover plate 23, Figs. 2 and 3. The operating lever 20 has a forward feeding motion and opposite non-feeding return motion along a slot as at 23a between the gearing compartment and its cover plate. The cutter blade 16, normally clear of the tape path also is actuated by the operating lever 20 in a manner to cut off the selected length of tape following stoppage of its forward movement, either by further forward movement of the operating lever or in association with its return movement.

Referring particularly to Figs. 3 and 4, the tape travels, gummed face down, to and past moisture applying means comprising an absorbent or capillary applicator, herein an inverted brush 25, and a vertically opposed guiding and presser element 26 shown as a freely rotatable vertically movable roller or roll unit journaled between supports on the side frames, one of which is seen at 27 in Fig. 4. The tape path between the severing means 15, 16 and the moistening means is defined as by an underguide 28, Fig. 4, and a cooperating top guide 29, Fig. 3, adapted for lifting to expose the tape path when desired.

The brush moistener 25 is removably positioned in a tank or reservoir 30 comprised in the liquid supplying and level controlling equipment with which the invention is more particularly concerned. The brush is disposed with its upper free end in moistening relation to the underface of the tape, being held in generally upright or forwardly inclined position as by a cross support 31 which is interrupted or apertured to admit liquid to the brush-holding portion of the tank 30. Beyond the moistening elements proper the tape may issue directly from the machine, or it may be further guided and supported for delivery in instances such as illustrated wherein the brush or other applicator is located somewhat rearwardly of the extreme fore-end of the machine. In such case a delivery guide or platform may be provided forwardly of the moistener, herein the outer top cover plate 32 removably secured to the tank as by screws 33, Fig. 2, and

having longitudinal ribs 34 along which the moistened tape is delivered.

Conductive moisteners such as the inverted brush 25 are subject to considerable variation as to the quantity of moisture conducted to and held available at their applying end, depending on the level of the liquid in the brush chamber. Also, under different atmospheric conditions, likewise with different types and weights of tape, it is desirable at times to apply more or less moisture than at others. For a given set of operating conditions there is a certain approximate optimum level for the liquid in the tank or reservoir such as 30. Such level should be continuous and uniform for the duration of the given conditions.

The present invention provides improved means adaptable to any machine of the class described for accomplishing the foregoing result, in such manner that the operator will have available a plurality of different levels for the liquid, any one of which may readily be selected at will and each of which is positively non-variably predetermined, as for example low, medium and high levels, each of which individually is always the same and is maintained uniformly at its precalculated height. That is, the invention insures that in shifting for example as between a high level and a medium level, the adjustment is compulsorily such that the predetermined medium level, say 1 1/4 inches or whatever has been determined as appropriate, always is afforded under the "medium" adjustment of the parts, and similarly as to each other available setting.

The liquid level control and maintenance unit or assembly is illustrated separately in Figs. 5 and 6 and in installed position in Figs. 1 to 4. It comprises, in combination with the tank 30 and its brush 25, an auxiliary liquid supplying and level control chamber or tank 40 adapted for attachment at a convenient location upon the given machine frame or housing, on the outer face of the left side frame 7 in the illustrated example. This control tank is cast, moulded or otherwise formed of suitable material to present a trough-like compartment closed at the bottom and open at the top as at 41. It is of a shape and size to conform to the general design of the particular machine, and to receive and adjustably support in inverted position a container for reserve liquid, such as the flask or bottle 42, Figs. 1 to 3 and Fig. 6. The auxiliary tank 40 and the container or flask 42 are relatively proportioned for seated positioning of the latter in the manner substantially as illustrated, the flask being held laterally between the side walls of the auxiliary tank 40 and resting in one or another of the selectively available inclined positions against the appropriately slanted tank rear wall 43.

The auxiliary compartment or tank 40 is detachably associated with the machine frame in a manner adapting it for ready removal and replacement as a unit together with the brush moistener tank 30. For this purpose the auxiliary tank is provided with front and rear wing-like projections or flanges 44, 45, each having a hook or hanger formation 46, 47 for seating on pins, bosses or the like projections 48, 49, Figs. 1 and 2, extending laterally from the side frame 7. Lateral spacing and positioning formations or bosses may be provided at the outer face of the inner side wall of the tank 40, one of which is seen at 44a, Fig. 5, for guiding and positioning

engagement with the laterally opposite portion of the machine frame.

At its lower forward portion the auxiliary chamber 40 has an apertured boss 50 tapped to receive 5 a threaded nipple or connection 51 to which is secured one end of a flexible tubing or hose connection 52. The main or brush tank 30 is similarly formed with an apertured boss 53, Figs. 2 to 4, on its wall adjacent the side frame upon 10 which the auxiliary tank 40 is to be mounted, this boss being near the bottom of the brush tank 30, at a position below the lowermost liquid level to be maintained. An angular fitting or elbow 54 is tapped into this boss 53 of the brush 15 tank 30 and projects laterally and rearwardly from the latter. Its rear end is tapped for reception of a threaded member 55 to which the forward end of the flexible tubular connection 52 from the auxiliary tank is attached.

20 As previously indicated, the main or moistener tank 30 is itself removably held between the side frames 7, where it is supported on one of the cross members 8, Figs. 3 and 4, and upon lateral projections at the inner faces of the frames, one 25 of which appears at 7a in Fig. 4. It is secured against unintentional forward displacement as by spaced depending members 35, 36 adapted to straddle the cross member 8. Thus it is evident that the flexibly connected double tank assembly 30 is constituted as a unit, as shown separately in Fig. 5, for installation and removal for cleaning, replacement and other purposes. Such manipulation of the assembly unit is quickly accomplished merely by tilting and withdrawing the 35 moistened tank with its contained brush and disengaging the auxiliary tank by lifting it from its hanger members 48, 49.

While the tubing connection to the main or brush tank 30 may be made at any convenient 40 lower point thereon, and may be extended below through or out around the adjacent portion of the side frame, the entire cooperative relation of this assembly unit to the machine and its housing is facilitated by the provision of a rearwardly 45 extending receiving and positioning recess and seating formation on the side frame, as represented at 70, Fig. 1. As there shown, said formation 70 serves to guide and support the elbow 54, while permitting it and the tank 30 to be inserted or withdrawn by a substantially straight horizontal sliding action, said formation being of 50 somewhat greater vertical extent than the elbow 54, adequate to permit the slight tilting of the front end of the tank for releasing it from the cross member 8, Fig. 4.

As best seen in Fig. 6, noting also Figs. 1 to 3, the auxiliary tank 40 incorporates means for controlling the liquid supply from the container or flask 42 to said tank and thence to the moistener tank 30, to afford any selected one of an available plurality of predetermined levels.

60 For this purpose the auxiliary tank 40 carries a plurality of controller or positioning formations, fixed stops or the like, each adapted selectively to set the container or flask 42 to deliver its liquid to a corresponding different but predeterminedly standardized level. In the illustrated embodiment these formations are presented by a flange or web 60 integrally or otherwise formed in the auxiliary tank 40 at its lower forward portion and extending longitudinally substantially centrally of the tank. It includes at its front end a plurality, herein two, inverted V-shaped fingers or stops 61, 62 at different levels 70 and directed upwardly and to the rear, for coop-

eration with the mouth of the flask or container 42. Below the lower finger 62 is a recess 63 having an inclined rear wall as at 64. This recess is of a size to receive and definitely position the neck of the flask, thereby to hold the latter with its mouth above the tank bottom wall, in what herein constitutes the lowermost setting, to afford the corresponding relatively low liquid level.

As indicated by the dotted line positions in Fig. 6, the flask 42 may alternatively be positioned with the lower or intermediate stop or finger 62 projected into its mouth, thus supporting the flask at a correspondingly higher intermediate level. Further, the pair of stop fingers 61, 62 are so proportioned and located relative to the flask mouth that the latter may be set down over both of them, in a further elevated position, to afford a corresponding higher and herein maximum liquid level. Additional similar stops may be provided if desired.

These level-controlling positioners, herein comprising the projections 61, 62 and the recess formation 63, 64 may be numbered or otherwise identified for ready reference in instructions to be supplied the operator as to the appropriate setting for the given operating conditions.

Where, as here illustrated, the container tank such as 40 is flexibly associated with the main or moistener tank as 30 and is detachably engaged with the particular machine in the manner of an accessory, it is adapted for installation upon existing machines of different types, and is equally available as original equipment. Its detachability further makes possible the interchangeable installation of different capacities of level-controller tanks and associated containers, as may be appropriate to different uses of a given machine.

My invention is not limited to the particular embodiment thereof illustrated and described herein, and I set forth its scope in my following claims.

I claim:

1. In gummed tape dispensing apparatus, in combination, a housing including side frames and a support for a tape supply, feeding and guide means for the tape, a moistener tank removably mounted between forward portions of the housing frames, a moistener therein presented in moistening relation to the guided tape, an auxiliary tank adapted for detachable mounting on the housing in liquid feeding relation to the moistener tank, interengageable members on the housing and the auxiliary tank for so mounting the latter, liquid conduit means including flexible tubing and end fittings at the respective tanks communicating between lower portions of the latter, an inverted open-mouth liquid container adjustably positioned in and by the auxiliary tank, and positive positioning formations at different heights in the latter for vertically adjusting the container to release its liquid at corresponding different predetermined levels.

2. A moistener assembly unit for gummed tape dispensers, comprising, in combination, a tank for liquid to be supplied to a moistener operatively disposed therein, said tank adapted for installation on such dispenser, a structurally separate open-top trough-like auxiliary tank for reserve liquid for maintenance of the liquid level in the

moistener tank, external tubular fittings at lower portions of the tanks and respectively opening into them, a flexible tubing connection having its opposite ends attached to the respective fittings, a flask-like liquid container removably supported in and by the auxiliary tank with its mouth-end down, a plurality of positioning formations fixed at different levels in the auxiliary tank below its top and selectively engageable with the container predeterminedly to adjust it for releasing its liquid at corresponding different levels, and attaching means on the auxiliary tank for securing it in upright position on the tape dispenser in operative association with the moistener tank.

3. In gummed tape dispensing apparatus, in combination, a housing including side frames and a support for a tape supply, guide means defining a path for the tape, a moistener tank, supporting means on the side frames for removably mounting said tank below a forward portion of the tape path, a separate auxiliary tank for reserve liquid for uniform level maintenance purposes, said auxiliary tank having a top portion open to atmosphere and receiving an inverted open-mouth liquid-supply container, means in the auxiliary tank for locating such container with its mouth at different selectively available predetermined discharging levels, interengageable positioning members on the auxiliary tank and an outer portion of a side frame of the housing for detachably associating them to present the auxiliary tank in liquid supplying relation to and rearwardly spaced from the moistener tank, conduit means including a separable tubing element and front and rear end fittings therefor affording communication for liquid from the auxiliary to the moistener tank, the front end fitting comprising an angular tubular element, and a forwardly open transverse recess leading from a front portion of the auxiliary-tank supporting side frame for slidably reception of said conduit means and adapting the latter and the tanks to be installed or removed as an assembly unit.

4. A moistener assembly unit for gummed tape dispensers, comprising, in combination, a tank for liquid to be supplied to a moistener operatively disposed therein, said tank adapted for installation on such dispenser, an open-top trough-like auxiliary tank for reserve liquid for maintenance of the liquid level in the moistener tank, means for removably mounting said auxiliary tank on a tape dispenser rearwardly of the first tank, conduit means interconnecting the tanks at their respective lower portions, a flask-like liquid container adapted for removable support mouth-end-down in the auxiliary tank, and container-engaging means in said auxiliary tank affording a plurality of predetermined positive adjusted positions for the container mouth, respectively at different levels in the auxiliary tank below its top and selectively available for releasing liquid from the container to the tank at said levels, said means including a finger shaped and proportioned to provide a supporting seat for a peripheral portion of the container mouth thereby to locate the latter at a selected adjusted position.

TREVOR R. GAUTIER.
